UNITED STATES PATENT OFFICE

ARTHUR M. TROGNER, OF EAST ORANGE, NEW JERSEY, ASSIGNOR TO WIRED RADIO, INC., OF NEW YORK, N. Y., A CORPORATION OF DELAWARE

FREQUENCY CHANGING SWITCH

Application filed October 8, 1926. Serial No. 140,377.

My invention relates broadly to signal transmission systems and more particularly to the construction of a frequency changing switch.

5 One of the objects of my invention is to provide a frequency changing switch for high frequency signaling circuits having relatively small electrical capacity for eliminating the absorption and radiation of energy at points 10 in the transmission circuits where this would introduce undesired losses.

Another object of my invention is to provide a low capacity switch construction for a frequency change switching system where 15 the length of the leads from the switching apparatus to associated apparatus is maintained extremely short.

A further object of my invention is to provide a frequency changing system in which 20 an inductance coil is carried by a frame structure, which is journaled for rotation, with contact devices disposed at selected points around the inductance coil for cooperation with fixed contacts adjacent the coil whereby 25 desired portions of the inductance coil may be effectively included in an electrical circuit.

A further object of my invention is to provide a rotatable inductance and switch structure with means for establishing good electrical connection with one end of the inductance while the inductance is free to revolve for the establishment of connection with selected points thereon for the inclusion of the desired amount of the inductance in an associated 35 electrical circuit.

Still another object of my invention is to provide means for establishing connection with a fractional part of a turn of an inductance system for securing accurate tuning of 40 the circuit in which the inductance is associated.

Still another object of my invention is to provide an inductance system including a rotatable coil structure with a plurality of co- 45 operating contacts adjacent thereto with means for accurately adjusting the position of the contacts with respect to the turns of the inductance after a broad setting of the co-operative position of the contacts and associated switch blades has been obtained for

the accurate setting of a circuit for a definite high frequency.

Other and further objects of my invention will be understood from the specification hereinafter following by reference to the accompanying drawings in which:

Fig. 1 is a perspective view of the frequency changing switch of my invention; Fig. 2 is a cross-sectional view taken through the switching apparatus in a plane adjacent one of the 55 end supports of the apparatus; Fig. 3 is a fragmentary view illustrating the relation of 60 one of the contact members and a connecting blade as employed in the switching apparatus; Fig. 4 illustrates a method of establishing connection with the end of the inductance where rotation is permitted through a distance of approximately 120 degrees; Fig. 5 is a cross-sectional view of a modified construction of my inductance system where means 65 are provided for establishing connection with fractional parts of a turn of the inductance at the end thereof; Fig. 6 is a perspective view showing one of the contact devices employed 70 in the modified construction of Fig. 5; Fig. 7 is a schematic view of the inductance system illustrating the arrangement of Figs. 5 and 6 for adjusting the inductance at one end to fractional parts of a turn; Figs. 8 and 9 illustrate a further modified form of my inductance system where provision is made for 75 the more accurate adjustment of the inductance values after a broad setting of the inductance values has been obtained.

In high frequency transmission systems in 80 which control of frequency is obtained by employment of piezo electric crystal devices, the added capacities and inductances in the connecting leads and auxiliary parts of the transmitting apparatus become comparable in 85 magnitude to the capacity and inductance of the circuit proper. By reason of the fact that these added inductance and capacity values cannot be readily varied, being inherent in the structure of the apparatus, they seriously 90 limit the flexibility of the circuit adjustments. In addition these added capacity and inductance values introduce undesired couplings 95 that by-pass energy from parts of the circuit where it would be useful and this results in 100

a reduction in the efficiency of the transmitter.

By my invention I provide a frequency change switch in which the length of the leads from the tap points on the coil to the switch contacts is maintained as short as possible. The capacity between the leads and the contacts is thereby reduced to a relatively low value. The inductance proper is mounted to rotate in such manner that contact making blades or members may be secured directly to the inductance coil at desired points for cooperation with stationary contacts positioned at desired points thereby eliminating all inductances inherent in flexible conductors heretofore employed. Capacities between the stationary contacts are reduced to a negligible value by placing them at widely separated points about the circumference of the inductance. The design of my inductance system is such that the desired values of inductance may be obtained within an extremely small space. Special provision is made for establishing connections for desired frequencies with selected lengths of the inductance.

Referring to the drawings in more detail, reference character 1 represents the supporting structure provided with extended arm members 2 and 3 and a bracket 4 upon which the conductive strip members 5, 6 and 7 are mounted extending longitudinally to the axis of the rotatable inductance. Contact devices in the form of spring jaws carried on adjustable U-shaped holders that are slid- able along the conductive strips 5, 6 and 7, are shown at 8, 9, 10, 11 and 21, respectively. The inductance coil is in the form of a strip 17 wound upon a rotatable frame made up of end portions 12 and longitudinally extending insulated members 14. The shaft 15 is journaled in the frame structure 1 in such manner that the entire inductance may be moved through a small arc by means of handle 16. The strip 17 is provided with switch blade members secured to selected points about the strip in cooperative relation to the stationary contacting jaws. I have represented these switch blade devices in the form of S-shaped clamps at 18, 19, 20, 22 and 26, each having an extended blade portion shaped to enter between cooperating side portions which form gripping jaws for the stationary contact members as represented at 8^a, 9^a, 10^a, 21^a and 11^a, respectively. The switch blades 55 may be milled from solid stock or bent to shape from metallic strips as represented. In each instance the spring jaws as represented in Fig. 3 at 8^a may be adjusted in position along the conductive strip by means of the U-shaped carrier and may be fixed at a selected position along the conductive strip by means of a set screw represented at 8^b.

For the purpose of illustrating the invention, the rotatable inductance has been shown in Fig. 1 as being arranged for movement to

two different positions. In the position shown, the switch blade 18 is in engagement with spring jaws 8^a, while switch blade 20 is engaged with spring jaws 10^a. By grasping the handle 16 and shifting the switch to the second position the switch blades 18 and 20 leave the jaws 8^a and 10^a while blades 19 and 26 enter the jaws 9^a and 11^a, respectively. A similar process occurs with respect to contacts on the other side of the switch which are hidden from view in the drawing in Fig. 1. Any desired number of conductive strips with cooperating contacts and switch blades may be employed, depending upon the arrangement of the electrical circuits.

In Fig. 4 I have shown one of the methods for making contact with the common connection at the end of the inductance when rotation within the limits of 120 degrees is necessary and where good electrical connection must be established eliminating all flexible contacts of varying inductance. From frame structure 30 I provide an extending resilient strip 29 which is in turn secured to a resilient strip 28 which connects with the end of the inductance strip 17 at the point 27. The resilient strips 29 and 28 are normally positioned as represented in Fig. 4 intermediate the limits of movement of the inductance switch. One limit of movement shows the resilient strips in dotted line position 28' and 29'. The other limit of rotation shows the resilient strips bent to position 29'' and 28''.

In order to secure more accurate adjustment of the inductance by including fractional parts of a turn of inductance in the circuit, that is a third of a turn, the construction shown in Fig. 5 may be employed. By this arrangement three auxiliary contact strips 31, 32 and 33 are provided at spaced intervals around the end of the inductance coil. These strips are connected by conductors 34 and 35 to a common point 36. A connection 38 is taken from a point 37 which is equi-distant from all of the contact strips 31, 32 and 33. On the last turn of inductance 17 there is secured at every quarter of a turn the S-shaped strip members 39, 40 and 41 carrying resilient face plate members 42, 43 and 44 which are moved into abutment or wiping contact with a selected one of the contact strips 31, 32 or 33. Corresponding positions of the switch blades on the inductance strip 17 may be selected for securing an accurate length of inductance in the electrical circuit. The inductance may be rotated to advance or retard the inductance by thirds of a turn to obtain the adjustment required. In some instance it is desirable to place the common connection to the inductance coil at some point along the coil and not necessarily at the end thereof. This is used wherever it is desired to provide tap-off points on the opposite sides of the common point.

5 The switching arrangement of employing the end adjustment feature of Fig. 5 is illustrated schematically in Fig. 7. As shown, corresponding contacts numbered 1 are in engagement with contacts carried by strip members 32, 5, 6 and 7. By rotation of the coil 17 in clockwise direction the next set of contacts which have been numbered 2 will be brought into connection with contacts carried by members 31, 5, 6 and 7. Upon 10 further rotation of the switch in a clockwise direction the contacts numbered 3 will be brought into engagement with member 32. As heretofore set forth any desired number 15 of contacts may be provided in accordance with the desired circuit arrangement. Further rotation will bring switch blade 4 in engagement with the contact carried by member 33.

20 In Figs. 8 and 9 I have illustrated a modified construction of switch by which more accurate adjustment may be obtained. In this arrangement the extended arms 2, 3 and 24 which carry conductive strips 5, 6 and 7 may be swung in an arc around the axis of the inductance system and adjusted in position by means of wing nuts 2^a, 3^a and 24^a operating on bolt members free to be moved in arcuate slots 1^a, 1^b and 1^c, respectively in the 25 frame structure 1. By this arrangement the contact jaws are adjustable both laterally and longitudinally with respect to the turns of the inductance so that an accurate amount of inductance may be selected for inclusion in the 30 transmitting circuit.

35 In lieu of the rotatable drum construction of the inductance I may construct the inductance in the form of a flat spiral coil which is rotatable about its center in the plane of the coil with the fixed contact supporting strip arranged parallel to the coil and in radial positions. By this arrangement the same electrical adjustments in the circuits 40 may be obtained although the mechanical arrangement of the parts is substantially different.

45 I have described my invention in certain of its preferred embodiments, but I desire that it be understood that modifications may be made and that no limitations upon my invention are intended other than are imposed by the scope of the appended claims.

50 What I claim as new and desire to secure by Letters Patent of the United States is as follows:

55 1. A frequency changing switch comprising an inductance member, means for rotatably moving said inductance member, a plurality of switch blades secured to selected 60 positions on said inductance member, and a plurality of contact members arranged adjacent said inductance member for cooperation with corresponding switch blades upon rotative movement of said inductance 65 member to a selected position.

2. In a frequency changing switch, a frame structure, a drum mounted for rotative movement in said frame structure, an inductance wound upon said drum, a plurality of switch blades secured to selected points along 70 said inductance, a plurality of contact members carried by said frame structure and arranged in position for cooperating with said switch blades when said inductance is rotated to selected positions.

75 3. In a frequency changing switch a frame structure, a rotatable drum journaled in said frame structure, an inductance carried by said drum, a plurality of switch blades secured to selected points along said inductance, contact 80 members corresponding in number to the number of said switch blades, said contact members being supported by said frame structure longitudinally of said drum in positions cooperating with said switch blades 85 whereby rotative movement of said drum effects an engagement of a selected set of said switch blades with corresponding contact members while disengaging another set of switch blades from corresponding contact 90 members.

95 4. In a frequency changing switch a frame structure, a rotatable drum journaled in said frame structure, an inductance carried by said drum, a plurality of switch blades secured at selected points to the turns of said inductance, a plurality of conductive strip members supported by said frame structure and extending longitudinally of said drum at points spaced about the periphery of said drum, contact members supported by said conductive strip members each having conductive faces thereon for establishing connection with the switch blades on said inductance, and means for rotating said drum for effecting an engagement of a set of switch blades with corresponding contact members while disengaging another set of switch blades from corresponding contact members.

100 5. In a frequency changing switch a frame structure, a rotatable drum journaled in said frame structure, an inductance carried by said drum, a plurality of conductive strips carried by said frame structure extending in spaced relation longitudinally of said drum, a plurality of switch blades arranged to be secured in selected positions along said inductance and a corresponding number of contact members slidably mounted on said conductive strips and movable longitudinally 105 with respect to the axis of said drum to a position corresponding to the path of movement of selected sets of said switch blades whereby rotation of said drum effects an engagement between a selected set of said switch blades and said contact members while disengaging another set of said switch blades from a corresponding number of said contact members.

110 6. In a frequency changing switch a frame 115

structure, a rotatable member journaled in said frame structure, an inductance carried by said rotatable member, a plurality of switch blades secured to selected points along said inductance, a corresponding number of fixed contact members arranged to be engaged by said switch blades during rotation of said inductance, and a resilient strip member secured to a selected point on said inductance and to said frame structure for establishing connection with said inductance throughout the period of rotative movement thereof.

7. In a frequency changing switch a frame structure, a rotatable member journaled in said frame structure, an inductance carried by said rotatable member, a plurality of switch blades secured to selected points along said inductance, a corresponding number of fixed contact members arranged to be engaged by said switch blades during rotation of said inductance, and a resilient strip member secured to the end of said inductance and to said frame structure for establishing electrical connection with said inductance throughout the distance of its rotation while effecting an engagement of one set of said switch blades with a corresponding number of said contact members and a disengagement of another set of said switch blades from others of said fixed contact members.

8. In a frequency changing switch a frame structure, a rotatable drum journaled in said frame structure, an inductance carried by said drum, a plurality of switch blades adjustably secured at selected points to the turns of inductance on said drum, contact members carried by said frame structure for cooperation with said switch blades upon rotation of said drum, and means for establishing connection with a fractional part of the end turn of said inductance for accurately selecting the effective value of said inductance.

9. In a frequency changing switch the combination of a frame structure, a drum rotatably mounted in said frame structure, an inductance carried by said drum, switch blades secured to selected points on said inductance, contact members supported from said frame structure for co-operative engagement with said switch blades upon rotation of said inductance, and a separate set of switch blades secured to the last turn of said inductance with a cooperating set of separate inductance with one set of said first mentioned switch blades for engagement with a corresponding set of contact members.

10. In a frequency changing switch a frame structure, a rotatable drum journaled in said frame structure, an inductance carried by said drum, a plurality of switch blades adjustably secured at selected points to the turns of inductance on said drum, contact

members carried by said frame structure for cooperation with said switch blades upon rotation of said drum, a plurality of separate switch blades secured to fractional parts of the last turn of said inductance, and a set of cooperating fixed contacts disposed about the last turn of said inductance whereby a fractional part of the last turn of said inductance may be included in circuit with the remainder of said inductance upon rotation of said inductance to a selected position.

11. In a frequency changing switch the combination of a frame structure, a drum rotatably mounted in said frame structure, an inductance carried by said drum, switch blades secured to selected points on said inductance, contact members supported from said frame structure for co-operative engagement with said switch blades upon rotation of said inductance, separate switch blades secured to fractional parts of the last turn, separate contact members each connected in common and arranged to cooperate with said last mentioned set of switch blades for effectively including a fractional part of said inductance in circuit with a selected portion of the remainder of said inductance.

12. In a high frequency switching system a frame structure, a rotatable drum journaled in said frame structure, an inductance carried by said drum, a plurality of switch blades secured at selected points along said inductance, a plurality of circumferentially movable frame members pivotally mounted on said frame structure each of said frame members carrying contact devices for cooperation with said switch blades, rotative movement of said drum effecting an engagement or disengagement of sets of said switch blades with said contact devices said contact devices being adjustable laterally and longitudinally with respect to the turns of said inductance.

13. A frequency changing switch comprising a rotatively mounted inductance member, a plurality of switch blades secured to selected positions on said inductance member, and a plurality of contact members arranged adjacent said inductance member for cooperation with corresponding switch blades upon rotative movement of said inductance member to a selected position.

14. In a frequency changing switch, a frame structure, an inductance member mounted for rotative movement in said frame structure, a plurality of switch blades secured to selected points along said inductance, a plurality of contact members carried by said frame structure and arranged in position for cooperation with said switch blades when said inductance is rotated to selected positions.

15. In a frequency changing switch, a frame structure, a rotatively mounted inductance journaled in said frame structure, a plurality of switch blades secured to selected points along said inductance, contact mem-

bers corresponding in number to the number of said switch blades, said contact members being supported by said frame structure in positions cooperating with said switch blades 5 whereby rotative movement of said inductance effects an engagement of a selected set of said switch blades with corresponding contact members while disengaging another set of switch blades from corresponding contact members.

10 ARTHUR M. TROGNER.
